[57] **CLAIM**

The ornamental design for a planter, as shown and described.

DESCRIPTION

FIG. 1 is a perspective view of my planter, showing my new design, the broken line showing a portion of the handle for illustrative purposes only and forming no part of the claimed design;

FIG. 2 is a top plan view thereof;

FIG. 3 is a side elevational view thereof, the side opposite being a mirror image;

FIG. 4 is an end elevational view thereof;

FIG. 5 is an opposite end elevational view thereof; and,

FIG. 6 is a bottom plan view thereof.
